UNITED STATES PATENT OFFICE.

FRANK A. GIRA AND JOHN H. GFELL, OF BELLEVUE, OHIO.

TIDY-HOLDER.

SPECIFICATION forming part of Letters Patent No. 411,188, dated September 17, 1889.

Application filed June 25, 1889. Serial No. 315,481. (No model.)

To all whom it may concern:

Be it known that we, FRANK A. GIRA and JOHN H. GFELL, citizens of the United States, residing at Bellevue, in the county of Huron 5 and State of Ohio, have invented certain new and useful Improvements in Tidy-Holders; and we do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to certain new and useful improvements in tidy-holders of that class formed of spring-wire of a single piece bent into the required shape to form clamping-arms, which embrace the piece of furniture to which it is applied upon opposite sides, with the tidy between one set of arms and the article of furniture to which it is applied.

20 The invention has for its object, in addition to the production of an improved tidy-holder, to produce a holder the employment of which will produce satisfactory results, and by which all danger of marring or injuring the chair or other piece of furniture is 25 avoided.

30 We are aware that it has been heretofore proposed to form tidy-holders of various forms from a single piece of spring-wire, and therefore do not seek to cover such construction, broadly, but restrict ourselves to 35 our peculiarities of construction.

40 The invention is clearly illustrated in the accompanying drawings, which, with the letters of reference marked thereon, form a part of this specification, and in which—

45 Figure 1 is a perspective view of our improved holder. Fig. 2 is a side or edge view of the same. Fig. 3 is a vertical section illustrating the same applied to a chair-back.

50 In the form of holder most resembling ours the ends of the wire composing the holder are bent outward at right angles to the arms of the holder and at right angles to the clamping arms or jaws, so as to engage under the back-rail of the chair at the top and prevent

the rising up of the holder. This we wish to avoid, as it is impossible to apply or take off the holder without marring the chair.

The invention in the present instance resides in the peculiarities of construction of 55 the holder, as more fully hereinafter described, shown in the accompanying drawings, and then particularly pointed out in the appended claim.

Like letters of reference indicate like parts 60 throughout the several views in which they occur.

Referring now to the details of the drawings by letter, A designates the holder, which is formed of a single piece of wire of suitable size best adapted for the purpose. This wire is first bent at the center of its length to form the loop a, which may be of any desired shape, but preferably practically square, as shown, this form having been found best 70 suited to hold the tidy in the form of a rosette, the angles forming much better holds on the tidy than the wire of a round loop. From this loop the wires are bent upward a short distance, being preferably inclined 75 slightly outward from each other, and then are bent at right angles to the vertical portions to form the horizontal portions b, which in use are adapted to rest upon the top of the top cross-bar of the chair-back or the 80 other piece of furniture on which it is applied. From these horizontal portions the wires are bent at right angles, or substantially so, to form the vertical arms c, which extend slightly below the lower portion of 85 the loop, where they are bent or curved, as shown at d, and again extended upward, but, instead of being arranged in the same vertical plane with the arms c, are inclined toward the loop portion, so that when these 90 upwardly-extending arms e reach the upper end of the holder they are about midway of the horizontal portions b. The ends of the wire are here coiled around in a plane parallel with each other, as shown, extending toward the rear of the holder.

95 In practice the holder is applied as shown in Fig. 3. The inclined arms e are important. They yield to allow the holder to be readily applied without marring the chair, 100

and when the holder is in place they press with sufficient force against the chair to firmly hold the holder and tidy in place, and from practical test have been found to serve 5 much more efficiently than were they bent parallel with the other arms. The coiled ends of the wire form a hold for the fingers in removing the holder.

- What is claimed as new is—
10 The tidy-holder described, formed of a single piece of wire bent to form the loop *a*, the

horizontal portions *b*, the vertical arms *c*, vertical inclined arms *e*, and the coiled free ends, substantially as herein shown and described.

In testimony whereof we affix our signatures in presence of two witnesses. 15
